TREATMENT OF HYDROCARBON OILS

Jacque C. Morrell, Chicago, Ill., assignor to Universal Oil Products Company, Chicago, Ill., a corporation of South Dakota

No Drawing. Application March 25, 1932
Serial No. 601,297

3 Claims. (Cl. 196—36)

This invention relates more particularly to the treatment of relatively low boiling cracked hydrocarbons although similar hydrocarbon mixtures produced in the straight-run distillation of crude oils and from other sources may also be treated by the process.

More specifically the invention is concerned with a process for treating and refining hydrocarbon oil mixtures of approximate motor fuel boiling range while in heated vaporous condition, the process being peculiarly adapted to produce primarily treating effects leading to stabilization of such distillates and also to regenerate the desirable properties which may have been lost on prolonged storage. Cracked hydrocarbon oils are characterized by the presence of undesirable amounts of gum-forming hydrocarbons.

The present invention is directed toward more selective removal of the gum-forming constituents and in one specific embodiment comprises the treatment of hydrocarbon oil vapors in heated vaporous condition with aqueous solutions of borates.

The most generally known member of the class of compounds known as borates is sodium tetraborate ($Na_2B_4O_7 \cdot 10H_2O$) ordinarily known as borax, although analogous compounds of the other alkaline metals are known and also other compounds with sodium such as, for example, the metaborate ($NABO_2 \cdot 4H_2O$), which is readily obtained by fusing together the necessary proportions of boric acid and sodium carbonate. Acid borates may be employed and may be produced by fusing mixtures of borax and boron trioxide, and perborates may also be employed.

While considerations of cost and availability will usually dictate the use of borax solutions in the treatments comprised within the scope of the invention, other borates of sufficient solubility may be used, alone or in combination therewith, when found advantageous. The following table shows the solubility of borax in water at varying temperatures, the figures given indicating the amount of anhydrous borax dissolved by 100 parts by weight of water.

Temperature °C.	Solubility
5	1.3
21.5	2.8
30	3.9
45	8.1
50	10.5
55	14.2
60	19.9
70	24.4
80	31.4
90	40.8
100	52.3

the temperature, fairly concentrated solutions are utilizable, since the treatments are ordinarily conducted at the elevated temperatures corresponding to the mean boiling point of the hydrocarbon fractions of approximately motor fuel boiling point range evolved from the fractionators of cracking plants. Thus treatments may be applied at temperatures between the approximate range of 250 to 600° F. and pressures from atmospheric to several hundred pounds per square inch may be employed whenever advantageous from an operating standpoint or when necessary to obtain the optimum temperature of treatment. When relatively high temperatures are found by trial to be preferable the higher pressures may be employed, whereas if only moderate temperatures are found to be the best in any particular case, it may at times even be worth while to conduct treatments under substantial sub-atmospheric pressures, under which conditions temperatures as low as 100 to 150° F. may be utilized, with corresponding modification in the treating effects produced.

The process requires only simple treating equipment such as vertical treating towers containing some type of inert spacing material through which the vapors to be treated may be passed upwardly counter-current to descending streams of treating solutions introduced above the filling material. When more accurate control is desired the tower may be provided with regularly spaced trays such as bubble trays or different types of baffles. To prevent undue concentration of the solution with attendant precipitation of solid salts and possible clogging or channeling in the treater, regulated amounts of steam may be mixed with the vapors undergoing treatment to increase the partial pressure of the water-vapor above the solution.

The use of strong borax or other borate solutions has been found effective in reducing polymerizable constituents and resinous materials, thereby improving the color and stability of the gasoline and may also have a substantial effect upon the sulphur content. The treatment is also especially adaptable to the treatment of deteriorated gasolines to restore their original properties as regards low gum content and high knock rating.

Among the examples of results obtainable by the use of borate solutions according to the process of the invention a treatment of cracked vapors of approximate gasoline boiling point range from a plant operating upon Pennsylvania fuel oil may be considered. Such vapors, arising from the primary fractionator of the cracking plant, may be under a temperature of approximately 275° F. and a pressure of 60 pounds per square inch. By passing these vapors upwardly countercurrent to an approximately 60% borax solution (corresponding to a saturated solution under the conditions of operation) a treatment of the vapors may be ef-

60 Since the solubility increases markedly with 110

fected as indicated by the change in properties evident by consideration of the "untreated" and "treated" columns in the following tabulation, the untreated column showing the quality of gasoline producible by simple fractionation without vapor phase treatment.

	Untreated	Treated
10 Gravity °A. P. I.	60.8	61
End point °F.	425	423
Color, Saybolt	14	29
Color after 4 hrs. exposure to sunlight	6	24
Gums by copper dish	210	15
Total sulphur %	0.14	0.09
Octane number	70	71

15 From the preceding example it will be apparent that the color, color stability and gum content have been substantially improved, and when it is considered that the total amount of borax solution may be as low as that equivalent to 3 pounds of borax per barrel of finished gasoline, it will be seen that the process possesses definite advantages, particularly due to the fact that the gasoline has been stabilized without loss of antiknock 25 value.

As already intimated earlier in the specification, the process may be employed to regenerate the original quality of cracked gasolines which have deteriorated upon long storage. As a characteristic example of this phase of the invention, a tabulation may be given to show the properties of a Pennsylvania acid treated cracked gasoline compared with its properties after 7 months' storage and with the properties of a gasoline made by rerunning the stored material against a solution of borax at the rate of two pounds per barrel by the countercurrent method disclosed in the first example.

REGENERATION TESTS

40 3 1/2# acid treated Pennsylvania gasoline stored 7 months

Properties	Original gasoline	Stored gasoline 7 months	Steam distilled	Rerun and borax treated
45 Gravity, °A. P. I.	59.4	56.0	58.4	58.2
Color, Saybolt	30	-3	7	26
Gum, Mg./100 cc copper dish	33	1,060	63	30
50 Octane number	71	45	65	65

100 A. S. T. M. distillation

I. B. P. °F.	114	133	135	136
55 5%	134	161	160	161
10% 156	156	176	174	176
20% 190	190	202	197	199
50% 255	255	266	257	260
E. P. °F.	327	334	325	326
60 % over on steam still	347	361	347	350
		93	93	

While the general effect of the treatment is evident from a consideration of the table, it may be specially noted that owing to losses of light ends on storage the octane number would be lower even though no other changes had occurred in the gasoline. It is also to be noted that the color is higher and the gum content lower than the gasoline produced by simple redistillation of the stored product, these results also showing the effect of the borax treatment.

The foregoing specification and examples have described the process of the present invention and shown its value as a treating method, but neither the specification nor the numerical data given are to be construed as imposing corresponding narrow limitations upon the generally broad scope of the invention.

I claim as my invention:

1. A process for refining hydrocarbon oil to remove gum and gum-forming components therefrom, which comprises subjecting the said hydrocarbon oil while in heated vaporous condition to the action of an aqueous solution of a water soluble borate, and adding steam to the vapors to prevent undue concentration of the solution.

2. A process for refining cracked hydrocarbon oil for the purpose of removing gum and gum forming components therefrom, which comprises subjecting the said hydrocarbon oil while in heated vaporous condition to the action of an aqueous solution of a water soluble borate, and adding steam to the vapors to prevent undue concentration of the solution.

3. A process for refining cracked hydrocarbon oil for the purpose of removing gum and gum forming components therefrom, which comprises subjecting the said hydrocarbon oil while in heated vaporous condition to the action of an aqueous solution of a sodium tetraborate, and adding steam to the vapors to prevent undue concentration of the solution.
